UNITED STATES PATENT OFFICE.

EMIL F. LINKE, OF HARTFORD, CONNECTICUT, ASSIGNOR TO THE THORNE
TYPESETTING MACHINE COMPANY, OF NEW YORK, N. Y.

TYPE-DISTRIBUTING MACHINE.

SPECIFICATION forming part of Letters Patent No. 651,551, dated June 12, 1900.

Application filed December 31, 1898. Serial No. 700,799. (No model.)

To all whom it may concern:

Be it known that I, EMIL F. LINKE, a citizen of the United States of America, and a resident of Hartford, in the county of Hartford and State of Connecticut, have invented certain new and useful Improvements in Type-Distributing Machines, of which the following is a specification.

This invention is an improved machine for "loading" type, type-matrices, or similar matter into the channels of type or matrix distributing machines, the object being to provide improved and reliable means for automatically injecting the lines of type matter into those channels only which by the progress of the distributing operation have become emptied of their type to any desired predetermined extent without interrupting the distributing operation and without the services of the attendant, save occasionally for the insertion of a new column or galley of type when the previous column has by the successive loading operations been transferred to the channels of the distributing-machine.

This invention comprises also improved means for feeding forward the column of type, for detaching the succeeding foremost lines singly therefrom, for positively "breaking" from the column the lines of type which may have become matted together during the previous printing or stereotyping operations, an improved guard device for cushioning the force of impact of the feeding movement of the column of type, and means for intermittently removing the tension of the feeding-spring from the column and from the injecting devices during the operation of injecting the detached line into the distributing-machine.

The invention further comprises improved features of construction and arrangement tending to facilitate the manipulation and control of the mechanism. These include a controller by means of which the trigger of the automatic starting device may at any time be withdrawn by the attendant from its operative position, so as to arrest the operation of the loading mechanism to permit all of the distributing-channels to become entirely empty or for any other purpose; an

automatic stop or knock-off device by means of which the operation of the loading mechanism is also stopped when the galley is emptied of its column of type; a hinged frame 55 upon which the loading mechanism is mounted, thereby permitting the entire mechanism to be swung aside for examination, adjustment, or repairs, and a cover-plate for the series of channels in the distributor, serving 60 as an abutment for the follower-springs and provided with one or more slots which by moving the cover-plate may be brought into coincidence with any one of the type-channels to allow of the ready removal therefrom 65 of the followers and their springs.

This invention, although applicable to other types of distributing-machines, is herein shown as being applied to the distributing-cylinder of a type-setting machine of the class 70 shown and described in the United States Patent to J. Thorne, No. 372,187, of October 25, 1887. That machine is provided with a stationary composing-cylinder 23 and with an intermittently-rotating distributing-cylinder 75 18, located above and concentric with the composing-cylinder. The distributing-cylinder is provided with type-receiving channels which run longitudinally of the cylinder and are located at equal distances apart 80 around the periphery thereof. The composing-cylinder is provided with similar channels located in a corresponding relation around its periphery, the upper ends of those channels being provided with wards set in 85 differing combinations, each of which permits only those type which are nicked in accordance with the combination of its wards to enter from the channels of the upper or distributing cylinder during the intermissions 90 in the rotation thereof. These intermissions occur just when the two series of channels in the two cylinders are coincident, thereby allowing the type in the distributing-cylinder which have arrived at their proper channels 95 in the composing-cylinder to drop past the wards into these channels.

Figure 1 of the drawings is a plan view of my improved mechanism, showing in connection therewith a fragment of the distributing-cylinder and its channels into which the type is to be loaded. Fig. 2 is a front view pro-

jected from Fig. 1, showing in addition thereto a portion of the driving-shaft and gearing of the machine, by means of which movement is transmitted to the loading mechanism. 5 Fig. 3 is an end view projected from the right-hand side of Figs. 1 and 2. Fig. 4 is an end view in section taken on the line 4 4 of Figs. 1 and 2. Fig. 5 is a plan view in section taken on the line 5 5 of Fig. 6. Fig. 6 is a front 10 view in section taken approximately along the line 6 6 of Fig. 5. Fig. 7 is a plan view, and Fig. 8 a left-hand end view, showing the line-engaging devices of the mechanism in a different position from those in which they are 15 represented in Figs. 1 and 5. Fig. 9 is a plan view representing the line-engaging devices in still another position, illustrating the operation of the guard-arm by-pass. Fig. 10 is a plan view of the driving mechanism and 20 the clutch device, the latter being shown just at the moment of release from its detent. Fig. 11 is a front view projected from Fig. 10 and showing in addition thereto the automatic starting device and the manual and automatic 25 stop devices in section taken substantially along the line 11 12 of Fig. 8. Fig. 12 is a fragmentary view taken on the same section-line, showing the trigger of the automatic starting device withdrawn below the plane of 30 rotation of the followers by the operation of the stop device whether manually or automatically operated. Fig. 13 is a left-hand end view in section taken approximately along the line 13 13 of Fig. 1, with the slot of 35 the type-channel cover moved into coincidence with the plane of the section. Fig. 14 is an end view of a modified form of stop device which like that of the previous figures is adapted to be operated manually or automatically. 40

The terms "front," "rear," "right," "left," "upper," "lower," and other similar terms are herein used in their relative instead of their absolute sense. For example, the view 45 shown in Fig. 2 is herein described as a "front" view of the loading mechanism, although this mechanism is preferably placed upon the rearward side of the type-setting machine, and therefore this view, regarded with reference 50 to the entire machine, would be a rear view thereof.

This loading mechanism in the preferred embodiment herein shown is mounted upon the framing 15, which is pivotally attached to 55 a portion of the frame 16 of the type-distributing machine by means of the hinge-pin 17, upon which the entire mechanism may be swung outwardly away from the distributing-cylinder 18 of the machine, so as to allow of 60 ready access to all parts of that cylinder or to the loading mechanism. The device is secured in its inward or operative position, as best shown in Figs. 1, 3, and 4, by means of the bolt 19, which passes through the hub 20 65 of the frame 16. The T-head of the bolt when turned into coincidence with the slot 21 in the framing 15 allows that framing to be swung

to its open position away from the hub 20, and when turned crosswise of the slot, as shown in Fig. 4, clamps the framing in position against that hub by means of the hand-nut 22. The vertical main shaft 24 is fitted to rotate in bearings in the framing 15 and is provided with a series of actuating-cams, each of which will be described in connection with the device which it operates. The axis of the main shaft 24 is in line with the axis of the driving-shaft 25 when the loading mechanism is in its operative position. 70

The driving-shaft 25 is journaled in the 80 bracket 26, attached to or integral with the frame 16, and it receives a regular rotary motion by means of the bevel-gears 27 and 28 from any convenient shaft, as 29, of the type-distributing machine. 85

The column 30 of the type matter to be loaded into the channels 31 of the distributing-cylinder 18 is contained in an ordinary removable galley 33, which is supported in a corresponding recess in the framing 15, with 90 its leading end in close proximity to the line-injector, being held endwise to place by means of the latch 39. The faces of the type at the front of the galley are shut in and protected by means of the door 34, which is preferably provided with a pane 35, of transparent glass, through which the progress of the column may be observed by the attendant. The door is pivotally attached by means of the H-shaped link 36 to suitable hubs 37 of 100 the framing 15, so that the door may, upon being released from its latch 38, be pushed longitudinally backward and then swung open to the position represented by dot-and-dash lines in Fig. 1. 105

The injector for transferring or loading the lines of type from the galley into the channels of the distributing-cylinder is herein shown to consist of a slide 40, which is located in line with one of the stopping positions of the type-channels 31. That slide is fitted to reciprocate in guiding-ways in the framing 15 to an extent represented by comparison of the extreme positions of the slides shown in Figs. 1 and 5. The reciprocating 115 movement of the injector-slide is imparted by means of the cam 41, fixed on the shaft 24 and operating through the medium of the bell-cranked arm 42 and the link 43. The type-engaging end of the injector is preferably provided with a facing 44 of celluloid, compressed fiber, or other similar substance to avoid damaging the character-faces of the type. The cam 41 is so formed and timed with relation to the movements of the distributing-cylinder as to move the injector forward during each intermission in the rotation of the cylinder. During the return movement of the injector as soon as its type-engaging end has been drawn back beyond 125 the plane of the faces of the type in the column the latter is moved forward far enough to bring its next leading line of type into the path of movement of the injector against the 130

stop 64 in position to be loaded into the succeeding channel of the cylinder at the next stroke of the injector. This forward feeding movement of the column is imparted by 5 means of a column - pusher, which, as best shown in Figs. 4 and 5, extends through the space between the door 34 and the galley 33 and engages behind the rearmost line of type in the column. For convenience of manipulation the column - pusher is preferably composed of two separable parts—the pusher-blade 45 and the carriage 48—the base 46 of the pusher-blade being fitted to slide transversely, as best shown in Fig. 6, in the column - pusher carriage 48. That carriage is 10 fitted to slide in the framing 15, beneath the type-galley and parallel therewith, far enough to enable the column - pusher to traverse the entire length of the galley. By this arrangement the column - pusher can be withdrawn laterally from its carriage by opening the door 34, or both the pusher and its carriage may be withdrawn longitudinally from the 15 mechanism by swinging the door entirely open.

The carriage 48 is provided with a pawl 51, which rests by gravity, aided, if necessary, by a spring, upon teeth cut in the upper surface of the feeding-rack 50, which is fitted to 20 slide in a longitudinal groove in the framing 15, beneath and parallel with the carriage 48, so as to enable the rack to reciprocate longitudinally to the extent of two or three of its teeth. The feeding impulse is intermittently imparted to the column by means 25 of the spring 53, attached between the rack 50 and the framing 15, the period and extent of the intermissions being controlled by a cam 54 on the shaft 24, which engages with an arm 55 of the rack and withdraws it from 30 the pawl 51, as shown in Figs. 5 and 6, during the time that the injector 40 is in front of the column, thereby transferring the pressure of the spring 53 to the cam from the column, and consequently from the side of the 35 injector 40, during the reciprocating stroke thereof, so as to allow it to move freely without side pressure.

The feeding-rack 50 is provided with a projecting handle 56, by means of which the operator may draw the rack backwardly away from the cam 54, so as to transfer the tension of the spring from the cam to the pawl 51, and thence to the pusher 45, when starting 40 the feeding operation upon a new column. The handle 56 is also useful to facilitate the release of the pawl 51 from the tension of the spring, when desired, by first drawing back the rack and then lifting the pawl out of contact therewith, the pawl being provided with an arm 52, which extends beyond the framing, so that it may readily be reached by the operator whenever it may be necessary to move the carriage 48 by hand.

45 As it frequently happens that some of the lines of type in the column become matted together during the printing or stereotyping

operations, means are provided for positively breaking or detaching each leading line of type from the column before injecting it into its channel. The means for this purpose embodied in the present invention consist of a breaker 58, which is pivotally supported upon one or more swinging links 59, so mounted on the framing 15 as to guide the type-engaging end 60 of the breaker behind the end of the injector 40 and against the feet of the next line of the column, which has at that time been fed forward into the plane of the injector, thereby breaking that line loose 80 from the column and moving it to the position shown in Fig 1. In Fig. 5 the breaker is shown at the opposite end of its movement with its type-engaging end outside of the plane of the injector 40.

85 As a means for moving the breaker through its desired stroke it is made to engage with the injector-slide 40. In the machine shown herein the outer end 61 of the breaker is extended into the plane of movement of the outer end of the injector-slide 40, the engaging surfaces being beveled, so as to facilitate starting the breaker from its extreme position. (Shown in Fig. 5.) The breaker is yieldingly held in this position by means of a spring 62, 95 attached to the framing 15. Thus by the operation of this breaker each succeeding foremost line of type is positively detached from the column upon each return movement of the injector-slide, so as to have a free line in 100 readiness for the succeeding operation of the injector.

The breaker is herein shown to be mounted upon two of the links 59, like a well-known parallel-ruler. This, however, is not essential to its operation, since one of those links, preferably located near the type-engaging end 60 of the breaker, would serve equally well, the opposite end of the breaker having a slotted connection with the injector or being guided in any convenient way in the path of movement thereof.

105 It is considered desirable to engage the "foot" ends of the type for the breaking operation in order to avoid or, at least, to reduce to a minimum the liability of marring or bruising the type-faces. Although the force of the impact or pressure against the foot of the line operates to carry the faces of the succeeding lines with an equal force against 110 the door or cover of the galley, still that pressure or impact is distributed over all the faces of all the cohering lines, thereby correspondingly lessening the liability of injuring the individual faces.

115 In order to cushion the force of impact of the feeding operation of the column against the stop 64, a guard-arm 65 is provided. This is pivotally mounted upon the framing 15, with its type-engaging end 66 extending 120 across the end of the column. The opposite end of the guard-arm is provided with a bypass 67, pivotally attached thereto and yieldingly held in the position shown in Figs. 1 and

5 by means of the spring 68, the arm being prevented from moving beyond this position by the contact of the two shoulders 69. The by-pass extends into the path of movement of 5 the cam 70 on the injector 40, which upon its return from the injection of each line moves the guard-arm, as shown in Fig. 7, into contact with the succeeding type-line just before the feed-cam 54 reaches a position which 10 allows the tension of the spring 53 to be transferred to the column. The force of impact of the forward feeding movement of the column is cushioned by the receding movement of the guard-arm, which is controlled by the cam 70 15 as the latter moves away from the by-pass 67 from the position shown in Fig. 7. The guard-arm is during the intermissions in its movement held in its outward or open position (shown in Fig. 8) by means of the spring 71, 20 attached to the framing 15. The succeeding forward or line-loading movement of the injector swings the by-pass 67 to the position shown in Fig. 9 without operating the guard-arm, which therefore is operated only by the 25 rearward or return movements of the injector. The type-channels in machines of this class are ordinarily provided with followers 85, which rest upon the type and by their weight, aided, if necessary, by the springs 30 84, serve to impel the type toward its lowest position in the channel. The upper ends of these followers project beyond the circumference of the distributing-cylinder, as shown in Figs. 1 and 13, so as to form shoulders 86 35 for engagement with the follower-lifter and the trigger of the automatic starting devices hereinafter described. The lifter 87 for these followers is pivotally mounted upon the framing 15 and engages with the cam 88. The end 40 of this lifter extends into close proximity to the distributing-cylinder and is adapted to engage beneath the projecting shoulders 86 of each of the followers as they successively reach the position of coincidence with the injector 45 40, as best shown in Fig. 13. The cam 88 is so formed and timed with relation to the rest of the mechanism as to raise and hold the follower above the level of the incoming line of type just in advance of and during 50 the line-loading movement of the injector 40, leaving that follower resting upon the top of that line and returning to its lowest or resting position in readiness for the succeeding follower. The construction and mode of operation 55 of this lifting device are substantially like the correspondingly-numbered device shown in United States Patent No. 614,662, of November 22, 1898, differing therefrom principally in the respect that the lifter of 60 the present machine is adapted to operate as a lever of the third kind, while in the machine of the patent referred to it operates as a lever of the first kind.

This loading mechanism is intermittently 65 operated by a driving device which is similar in its essential features to the device employed for a similar purpose in the machine of

the aforesaid patent, No. 614,662. The main shaft 24, which carries the cams for actuating the loading mechanism, is located, as already described, in line with the driving-shaft when the loading mechanism is swung into its operative position. (Shown in the figures of the drawings.) That driving-shaft 25 has fixed upon it a carrier 73, having in its periphery a shoulder 74. A plate 75 is fixed upon the cam 88, and thereby fixed to the shaft 24, and has a pawl 76 pivotally mounted thereon in the plane of the carrier 73. A projecting hook 77 of the pawl is adapted to engage with the shoulder 74 of the carrier, and the pawl is normally held toward its engaging relation with the carrier by means of the spring 78. (Shown in Fig. 10, in which the pawl is also shown to be in driving engagement.) 85

During the desired intermissions in the operation of the loading mechanism the pawl 76 is held out of engagement with the carrier, as shown in Fig. 1, by means of the detent 90, pivotally mounted upon the framing 15 and 90 engaging with the outer end 79 of the pawl. As herein shown, the detent is mounted upon the stud, which also forms the pivot for the lifter 87, although this is merely for constructive convenience and economy. While in the 95 detached position shown in Fig. 1, the pawl 76 under the tension of its spring 78 operates as a lever against the engaging detent 90, tending to turn the plate 75 and its shaft 24 backwardly, which movement, if permitted, would allow the hook of the detent to be struck by the shoulder 74 of the carrier at each rotation. This backward turning of the plate is, however, prevented by a latch 80, (best shown in Fig. 5,) which is pivotally 105 mounted upon the framing 15 and engages with a suitably-located rearwardly-facing shoulder 81 on the hub of the feeding-cam 54, being held into contact therewith by means of the spring 83. 110

The construction and mode of operation of the intermittently-operating driving device described in the preceding paragraph are substantially like those of the device shown in the Patent No. 614,662 above referred to; but the 115 automatic starting device herein shown for automatically releasing the carrier-pawl 76 from its detent 90, so as to permit the pawl to engage with its carrier and operate the loading devices whenever those channels which have 120 become emptied of their type to a predetermined extent arrive at the position of coincidence with the injector, is an important feature of the present invention and will now be described. The detent 90 is provided with a 125 trigger 91, (best shown in Figs. 11 and 12,) located close to the distributing-cylinder in a plane substantially coincident with that of the lowest position reached by the shoulders 86 of the followers 85 when their respective 130 type-channels are empty or when the type has receded to any desired stage in the distributing operation. The trigger is fitted to slide in a direction substantially coincident

with that of the rotary movement of the followers at the line-injecting position and is provided with an upwardly-extending shoulder 92 for engaging with the shoulders 86 of the respective followers. The trigger is connected by means of the rod 93 with the lower end of the pivotally-mounted detent 90, so that the trigger when engaged by one of the followers, as shown in Fig. 11, withdraws the upper end of the detent 90 from the carrier-pawl 76 and allows the latter to engage with its carrier, as shown in Fig. 10, thereby starting the loading mechanism upon one of its operations. The detent 90 and the trigger 91 are during the intermissions in that operation yieldingly held in the position shown in Figs. 1, 2, and 6 by means of the spring 94, (shown in Figs. 1 and 4,) attached to pins on the rod 93 and on the framing 15. The rod 93 is attached to a slotted arm of the detent 90, so as to allow of varying the angular movement of the detent. Almost the first step in the operation of the loading mechanism is that of raising the follower 85 away from the shoulder 92 of the trigger, as shown in Fig. 6, thereby disengaging these parts for the succeeding rotative step of the cylinder. Before thus lifting the follower, however, the trigger is pushed forward therefrom, so as to remove from the follower the lateral pressure of the trigger-spring 94. The detent 90 is provided with an arm 95, which extends into engaging relation with a cam-surface 96 of the plate 75, which immediately upon the starting of the loading mechanism, as shown in Fig. 10, comes in contact with the arm 95 and pushes the shoulder 92 of the trigger away from the follower, as shown in Fig. 11. The cam 96 is so formed and timed with relation to the rest of the mechanism as to allow the trigger and its detent to return again to their position (shown in Figs. 1, 2, and 6) for detaching the pawl 76 from the carrier at the completion of its rotation and to be in readiness for the follower of the succeeding type-channel, in case that channel should be emptied of its type sufficiently, to allow its follower to engage with the trigger.

As it is frequently desirable to entirely stop the operation of the loading mechanism at the will of the operator in case of a disarrangement of the type or to allow the distributing-channels to become entirely emptied of their type, a controlling device is provided, the construction and mode of operation of which are best shown in Figs. 10 and 11. The trigger 91 is mounted upon a cross-head 97, which is fitted to slide vertically in a suitable slideway in the framing 15. The lower end of the cross-head is inclined and rests upon a correspondingly-inclined portion of the controller 98, which is fitted to slide transversely to the direction of movement of the cross-head and extends to any point of the machine at which it may be most conveniently reached by the attendant or operator. Its range of movement, determined

by the screw 99 and the shoulder 100, is, as represented by a comparison of Figs. 11 and 12, sufficient to enable the controller when 70 in one position, as shown in Fig. 11, to support the cross-head, with the shoulder 92 of the trigger projecting into the zone of movement of the followers, and when in the other position to allow the cross-head to drop, so 75 as to withdraw the shoulder 92 below that zone of movement, as shown in Fig. 12, thereby permitting the distributing-cylinder to rotate without actuating the loading mechanism. It will be obvious that but one, and 80 either one, of the coengaging surfaces of the controller and the trigger-support need be inclined for the performance of this function. The dropping movement of the cross-head and its trigger may be by the force of 85 gravity alone or by the operation of a spring, as 89, according to the weight of the parts or their disposition with relation to the vertical. It is also desirable to have the loading mechanism stopped automatically whenever the 90 last line of each column has been fed out of the galley, so as to relieve the attendant or operator from the necessity of watching the progress of the loading operation. This feature is of great importance in connection 95 with a loading device which, like that of the present invention, is intended for use upon a type composing and distributing machine to be manipulated by a single operator, since that operator is thereby enabled to devote 100 his entire attention to the composing portion of the machine, excepting when the automatic stopping of the loading mechanism indicates that the column of type has all been loaded into the machine. The means for thus 105 automatically stopping the loading mechanism consists in the embodiment shown in the principal figures of the bell-cranked knock-off arm 108, which is pivotally mounted upon an ear of the framing 15 and extends immediately beneath the controller 98. This arm is provided with a connecting-rod 109, which extends substantially parallel with the path of the column-pusher carriage 48 and is provided with a pin or similar projection 110, 110 extending into the path of movement of the projection 49 of that carriage. The latter is so located that it will collide with the pin and thus operate the knock-off in pushing the last line of type from the column in front of 115 the injector 40, thereby raising the latched end of the controller 98 and allowing it to be withdrawn from beneath the trigger cross-head 97 to its non-operative position (shown in Fig. 12) by means of the spring 111, which 120 is attached between the controller 98 and a convenient fixed portion of the machine or framing. This spring is so disposed and connected as to exert its tension downwardly as well as longitudinally upon the controller, 125 thereby tending to carry the latter to and hold it yieldingly in its latched position. (Shown in Fig. 11.)

This loading mechanism may be adapted to

the loading of lines of differing lengths by suitably proportioning the respective parts, or its capacity in this respect may be modified within certain limits by adjusting the 5 stroke of the follower-lifter 87 or by substituting another lifter-arm having the desired stroke, or another and suitably-adapted mechanism with its own framing may be substituted by withdrawing the hinge-pin 17.

10 In order that the type-channel followers may be accurately adjusted and maintained in a uniform relation to the trigger and also to allow of the substitution of other followers of different length or springs of different 15 tension when changing the machine to operate upon a different width of column, it is desirable that these followers and their springs shall be readily removable by the operator. As a means of accomplishing these objects 20 the entire series of channels is provided with a cover-plate 101, which as applied to a cylinder is an annular plate extending entirely around the top of the cylinder, being held in position by the annular gib 102. The plate 25 is provided with a slot 103, corresponding in position with that of the type-channels, so that the slot may by shifting the plate be brought into coincidence with any one of those channels. That portion of the slot 30 which coincides with the position of the series of springs is enlarged to permit of the passage of the spring through the slot, the opening being closed by the screw-plug 104, the end of which is coincident with the bottom 35 surface of the plate, so that it may be moved along the series of springs without catching their upper ends. When it is desired to remove a spring or a follower, or both, the operator seizes the plate by its projecting 40 rim 105, which is preferably rounded like the rim of a hand-wheel and moves the slot 103 into coincidence with the desired channel. He then removes the plug 104, thereby permitting the removal of the spring and the follower. 45 This cover-plate may, if desired, be provided with additional slots 103, located at substantially equal intervals around its circumference, in order to lessen the extent to which the cover must be moved in order to 50 bring one of the slots over a desired channel.

A brief description will now be given of the operation of this device. A galley of type is placed in position, the carriage 48 is shifted to the rearward end of the galley, the column- 55 pusher 45 is inserted behind the bottom or rearward line of the column, and the door 34 is closed. The tension of the feeding-spring 53 is then transferred from the cam 54 to the pawl 51 of the carriage by drawing back the feed-rack one or two notches by means of its handle 56. During these preparations the mechanism remains in the position shown in 60 Figs. 1, 2, and 3, and during this time also the distributing-cylinder should be stopped or the trigger 91 should be retracted to the 65 position shown in Fig. 12 out of engaging re-

lation to the followers by means of the controller 98. The controller is then pushed forward to the position shown in Fig. 11, in which it is latched by its shoulder 100, and the distributing-machine may then be put in operation. The first follower 85, which is low enough in its channel to collide with the shoulder 92 of the trigger, moves that trigger and its connected detent 90 to the position shown in Fig. 11, thereby releasing the pawl 76 and allowing it to engage with its carrier 73, as shown in Fig. 10, thus inaugurating one of the intermittent rotations of the driving-shaft 25 and its actuating-cams. At the commencement of that rotation the cam 96, engaging with the arm 95 of the detent 90, moves the shoulder 92 of the trigger clear of the follower which actuated it, and the lifter 87 raises the follower to the position shown in Fig. 6. By this time the detent 90 is released from its cam 96 and is permitted to return to the position shown in Figs. 1 and 6 in readiness to collide with the ends 79 of the carrier-pawl and disengage it from its carrier 73. Meanwhile the injector 40 is moved by its cam 41 toward the distributing-cylinder, carrying into the coincident type-channel thereof the line of type which lies in its path of movement. During this forward movement of the injector the by-pass 67 is carried forward by its cam 70, as shown in Fig. 9, without operating the guard-arm; but upon the return movement of the slide, upon reaching the position shown in Fig. 7, the guard-arm is carried forward against the succeeding line of type of the column, so as to take the tension of the feeding-spring 53, now transferred from the cam 54 to the column after having been supported by that cam during the forward movement of the injector. The cam 70 of the injector is so shaped as to allow the guard-arm to recede as gradually as the timing of the parts will permit to the position shown in Fig. 1, so as to cushion the force of impact of the column against the stop 64. At this time also the breaker 58 is brought into operation by the movement of the injector, the type-engaging end 60 of the breaker being swung by the angular movement of its link into the plane of the foremost line of the column and against the feet thereof, moving to the position shown in Fig. 1 and forcibly breaking the foremost line from the column, in which position the line rests in readiness to be loaded into the succeeding emptied channel of the distributing-cylinder at the next operation of the loading mechanism. As the last line of the column is pushed in front of the injector 40 the projection 49 of the column-pusher 45 collides with the pin 110 and operates the automatic stop device, thereby withdrawing the trigger 91 out of the zone of movement of the followers 85, and thus stopping the operation of the line-loading mechanism. When it is desired to stop that mechanism before the completion of the column then in the galley,

the stop device is manually operated by lifting the latching-shoulder 100 of the controller clear of its catch.

The modified construction shown in Fig. 14 may be employed to advantage wherever the environment will permit. The cross-head 115 is fitted to slide vertically, as before, and is provided with the pivotally-attached controller 116, to the bell-cranked end of which is attached the spring 117, which thereby exerts a downward pressure upon the cross-head and a lateral pressure upon the controller, holding it against the catch 118, upon which the latching-shoulder 119 of the controller rests when the device is in its upper or operative position shown in the figure. The controller extends into engaging relation to the projection 49 of the column-pusher, so that the latter upon reaching the desired limit of its movement carries the controller laterally away from the supporting-catch 118, thereby allowing the cross-head to be drawn by the spring 117 to its lowest position, corresponding to that of the cross-head 97. (Shown in Fig. 12.) The controller may extend downwardly, as here shown, or upwardly, if preferred, to any point at which it may be most conveniently reached by the operator. It is also preferably provided with a stop-shoulder 120 to arrest its upward or starting movement at a point which permits its latching-shoulder 119 to pass over the catch 118. The framing 15, although shown in the drawings as being made up of several separate parts for convenience in constructing and assembling the mechanism, is herein described as a single element, inasmuch as it serves when in use as a single integral piece; so, also, does the bell-cranked arm 42, which is herein shown to consist of two members clamped together for convenience in adjusting the stroke and position of the injector, since the two members operate as an integral piece after being adjusted in proper angular relation. In like manner the column-pusher would be equally effective for the performance of its principal function of feeding the type if it were constructed in an integral piece, being herein shown to consist of two separable parts for convenience in manipulating the machine. The hinge-pin 17, upon which the framing 15 is pivotally mounted, is herein shown to be located at a point near the axis of the actuating main shaft 24, thereby bringing that shaft out of axial alinement with the driving-shaft 25 when swung away from its loading position. It is obvious, however, that the framing might be hinged upon or concentric with the main shaft itself, thereby keeping that shaft always in alinement with its driving-shaft. The matter to be loaded is hereinbefore referred to under the generic name of "type matter," which should be understood to include matrices and all other similar matter to which this invention is or may be found applicable.

The shoulder 92 of the trigger 91 is herein

shown to be located so as to be engaged only by the followers of those channels which have become entirely emptied of type. Obviously, however, the shoulder may be extended upwardly or the entire cross-head and its support be moved bodily upward or downward, so that the shoulder may be engaged by the followers at any desired plane or level, so as to reload the channels whenever the type therein have receded to the desired extent.

I claim as my invention—

1. In a machine of the class specified, in combination with a laterally-moving type-distributing channel thereof, and with a device for loading type into the channel, means operative with the lateral movement of the channel, for automatically starting the loading device in operation when the type in the channel recedes to a predetermined extent.

2. In a machine of the class specified, in combination with a laterally-moving type-distributing channel, an intermittently-operating type-loading device therefor, a detent for holding the loading device out of operation during the desired intermissions, and means operable with the lateral movement of the distributing-channel for automatically disengaging the detent from the loading device when the type in the channel reaches a predetermined point in its distribution.

3. In combination with a series of type-distributing channels, and with devices for loading type therein, means independently operable with each channel for automatically starting the loading devices to load that channel when the type therein recede to a predetermined extent.

4. In combination with a series of type-distributing channels, having an intermittently-operating type-loading device therefor, a detent for holding the loading device out of operation during the desired intermissions and means independently operable with each distributing-channel for automatically disengaging the detent from the loading device to load that channel when the type therein recede to a predetermined level.

5. The combination of a laterally-moving type-distributing channel, a type-follower therefor, intermittently-operating loading mechanism for injecting type into the channel, and detent mechanism for preventing the operation of the loading mechanism at the desired intermissions, extending into engaging relation with the type-follower at a predetermined plane in its lateral movement, whereby the loading mechanism is released and permitted to operate.

6. In a laterally-moving type-distributing machine comprising a distributing-channel and a follower for the type in the channel, loading mechanism for inserting additional matter in the distributing-channel, an intermittently-operating driving device for the loading mechanism, a detent for holding the driving means stationary during the desired intermissions, and means operable with the

- lateral movement of the channel-follower for disengaging the detent and releasing the driving mechanism when the type in the channel reaches a predetermined point in its distribution. 5
7. In a machine of the class specified, in combination with a laterally-moving type-distributing channel thereof, and with loading mechanism for inserting additional type matter into the channel, an automatic starting device for the loading mechanism, located in engaging relation to the follower, and means operable with the loading mechanism for disengaging the starting device from the follower. 10
8. In a machine of the class specified, in combination with a distributing-channel, a follower therefor, and intermittently-operating loading mechanism for inserting additional type matter into the channel, a starting device for the loading mechanism located in engaging relation to the follower, and a lifter for raising the follower again above the plane of the starting device. 15
9. In a machine of the class specified, in combination with a distributing-channel, a follower therefor, and loading mechanism for inserting additional type matter into the channel, a starting device for the loading mechanism located in engaging relation to the follower, means, as a cam, for disengaging the starting device from the follower, and a lifter for raising the disengaged follower out of engaging relation to the starting device. 20
10. In a machine of the class specified, the combination of a distributing-channel, a follower for the type in the channel, line-loading mechanism, comprising means for supporting a galley of type, means for cutting off the single lines of type from the galley and inserting them in the channel, and a lifter for raising the follower out of the way of the incoming type. 25
11. In combination with a series of intermittently and laterally moving type-distributing channels for uneven lines of type, loading mechanism therefor, comprising means for automatically finding and injecting type into those channels only which become emptied to a predetermined extent. 30
12. In combination with a series of intermittently and laterally moving type-distributing channels for uneven lines of type, a corresponding series of independent followers, intermittently-operating loading mechanism therefor, comprising, a lifter for the followers, and means for automatically finding and injecting type into the succeeding channels only as they become emptied to a predetermined extent. 35
13. In combination with a series of intermittently and laterally moving type-distributing channels, provided with followers, loading mechanism therefor, comprising, a lifter for the followers, means for cutting off lines of type from the column or galley and injecting them into the succeeding channels at one of the stopping positions thereof, an intermittently-operating driving device for the loading mechanism, and a starting device operable with the followers for putting the loading mechanism in operation at each of those channels which have become emptied of type to a predetermined extent. 40
14. In combination with a series of intermittently and laterally moving distributing-channels, provided with followers, loading mechanism therefor, comprising, a lifter for the followers, means for cutting off lines of type from a column or galley and injecting them into the succeeding channels at one of the stopping positions thereof, an intermittently-operating driving device for the loading mechanism, a detent for holding the loading mechanism stationary during the required intermissions, and means, operable with each of those channels which have become emptied of type to a predetermined extent, for disengaging the detent and releasing the driving device. 45
15. In combination with a series of intermittently and laterally moving distributing-channels provided with followers, loading mechanism therefor, comprising a lifter for the followers, means for cutting off lines of type from a column or galley and injecting them into the succeeding channels at one of the stopping positions thereof, an intermittently-operating driving device for the loading mechanism, a detent for holding the loading mechanism stationary during the required intermissions, and a trigger operatively connected with the detent and located in position to be engaged by each succeeding follower of those channels as it becomes emptied of type to a predetermined extent, when it reaches the aforesaid stopping position. 50
16. In combination with a laterally-moving type-distributing channel and its type-follower, an automatic starting device having a trigger located in engaging relation to the follower at a predetermined plane of its lateral movement of the follower. 55
17. In combination with the distributing-channel and with a follower therefor, an automatic starting device having a trigger located in engaging relation to the follower at a predetermined point in the path of movement of the follower, with means for withdrawing the trigger from the said path of movement. 60
18. In combination with the distributing-channel and with a follower therefor, an automatic starting device having a trigger located in engaging relation to the follower at a predetermined point in its path of movement, and a movable support for the trigger for enabling it to be moved at will into or out of the path of movement of the follower. 65
19. In combination with a series of intermittently and laterally moving type-distributing channels, provided with followers, an automatic starting device having a trigger located in engaging relation to the suc- 70 75 80 85 90 95 100 105 110 115 120 125 130

sive followers at the end of their required path of movement, and a movable support for the trigger for moving it at will into or out of engaging relation to the series of followers.

5 20. In combination with a series of intermittently-moving distributing-channels provided with followers, an automatic starting device having a trigger located in engaging relation to the successive followers at the ends of their required paths of movement, a support on which the trigger slides laterally with the followers when engaged thereby, and means as a cam for moving the trigger laterally away from the follower after each engagement.

10 21. In combination with a series of intermittently-moving distributing-channels provided with followers, an automatic starting device having a trigger located in engaging relation to the successive followers at the ends of their required paths of movement, a support for the trigger allowing it to move with the followers when engaged thereby, 15 and a controller for moving the trigger into and out of engaging relation with the series of followers.

20 22. In combination with a series of intermittently-operating distributing-channels provided with projecting followers, an automatic starting device having a trigger located in engaging relation to the successive followers when at the ends of their required paths of movement, a support for the trigger movable in a direction substantially parallel with that of the movement of the followers, and a controller engaging by means of an inclined surface with the trigger-support for moving the trigger into and out of the plane of rotation of the projecting coengaging members of the followers.

25 23. In a machine of the class specified, in combination with the intermittently-rotating distributing-cylinder thereof, intermittently-operating loading mechanism therefor, comprising, an injector located at a stopping position of the distributing-channels of the cylinder, means for feeding succeeding lines of type into the path of movement of the injector, and means for starting the loading mechanism in operation at these channels only in which the type has receded to a predetermined extent.

30 24. In combination with a series of intermittently and laterally moving type-channels, provided with followers, loading mechanism therefor, comprising, an injector located in coincidence with a stopping position of the channels, means for feeding the type successively into the path of movement of the injector, and an intermittently-operating driving device for the loading mechanism, operable with the followers in the channels for operating the loading mechanism only at 35 each of those channels in which the followers have reached a desired predetermined position.

25 25. In combination with a series of intermittently and laterally moving type-channels provided with followers, mechanism for supporting and feeding a column of type to the channels, a trigger for starting the column-feeding mechanism, located in engaging relation to the followers, and means operable with the column-feeding mechanism at a predetermined point in the movement thereof for moving the trigger out of engaging relation to the followers.

30 26. In a machine of the class specified, an intermittently-rotating distributing-cylinder provided with type-channels and followers therein, means for supporting a column of type, means for feeding the type from the column to the channel at the intermissions in the rotation thereof, a detent for holding the feeding mechanism out of operation, a trigger located in a predetermined plane of rotation of the follower for withdrawing the detent from the feeding mechanism, and means operative with the column-feeding mechanism for automatically moving the trigger out of the engaging plane of the follower, to prevent the release of the detent, thereby arresting the column-feeding operation at a predetermined point thereof.

35 27. In a machine of the class specified, the combination with a distributing-channel, and with a follower for the type in the channel, of automatic mechanism, comprising means for holding a column of type and for feeding the column longitudinally, intermittently-operating driving mechanism, a starting device for the driving mechanism located in engaging relation to the follower, and means operative with the column-feeding means for withdrawing the starting device out of engaging relation to the channel-follower at a predetermined point in the feeding movement of the column.

40 28. In combination with a series of laterally-moving type-distributing channels, and a column or galley of type, an intermittently-operating injector for pushing the separate lines of type into the succeeding channels, and a breaker operable by the injector upon its return from each injecting operation on each line for detaching the succeeding line of type from the galley in readiness for the succeeding movement of the injector.

45 29. In combination with an injector for removing the succeeding lines of type from a column or galley, means for feeding the succeeding lines into the path of movement of the injector, and a breaker operable by the injector upon its return stroke for detaching from the column the line of type to be removed by the succeeding movement of the injector, the breaker being mounted to swing out of the path of movement of the injector and its line of type during the forward or injecting movement thereof.

50 30. In combination with the described injector for lines of type, a breaker operable by the injector, mounted upon a link for guiding

it into and out of the path of movement of the injector.

31. In combination with an injector for lines of type, means for supporting a column of type and for feeding the succeeding lines thereof into the path of movement of the injector, and a breaker operable with the injector for engaging behind the end of the succeeding lines, and detaching them from the column in the direction of the return movement of the injector.

32. The combination of an injector for lines of type, means for supporting a column of type and for feeding the succeeding lines thereof into the path of movement of the injector, and a breaker operable by the injector upon the last portion of its return stroke for moving the breaker into contact with the foot end of the foremost line of type, to detach it from the column in readiness for the succeeding forward stroke of the injector.

33. In combination with means for supporting and feeding a column of type, a guard-arm for cushioning the force of impact of the feeding movement, and a reciprocating cam for controlling the movement of the guard-arm, the latter being provided with a by-pass device for engaging with the cam for allowing the latter to return without actuating the guard-arm.

34. In combination with means for supporting and feeding a column of type, a reciprocating injector for the type-lines, a guard-arm for cushioning the force of impact of the feeding movement, means for yieldingly holding the guard-arm out of engagement with the type, and a cam upon the injector for actuating the guard-arm upon the reciprocation of the injector in one direction, the guard-arm being provided with a by-pass for permitting the return movement of the cam without actuating the guard-arm.

35. In combination with means for supporting a column of type, a spring-actuated intermittently-operating feeding device therefor, and a cam for removing the actuating pressure of the spring at the desired intervals in the feeding movement.

36. In combination with means for supporting a column of type, an intermittently-operating feeding device therefor, comprising a pusher, a pawl, a reciprocating ratchet for the pawl, a spring for the forward feeding movement of the ratchet, and a cam for removing the pressure of the spring from the column at the desired intervals in the feeding movement.

37. In combination with means for supporting a column of type, an intermittently-operating feeding device therefor, comprising a pusher, a pawl, a reciprocating ratchet for the pawl, a spring for the forward feeding movement of the ratchet, and a cam for retracting the ratchet to bring its succeeding teeth into

engagement with the pawl as the column progresses.

38. In combination with an injector for removing the lines of type, means for supporting and feeding the succeeding lines of a column or galley of type into the path of movement of the injector, comprising a column-pusher, a pawl, a ratchet, a spring for the feeding movement, and a cam for retracting the ratchet to remove the tension of the spring from the column of type during the operations of the injector.

39. In a type-distributing machine having a series of type-channels provided with followers, a cover for the ends of the series of channels, having a slot movable into register with each channel of the series to permit the removal of the follower therefrom.

40. In a type-distributing machine, in combination with the type-channels thereof, provided with followers, and with actuating springs therefor, a movable cover-plate and abutment for the springs, provided with a slot which may be moved into register with any channel of the series to permit the removal of the follower therefrom, the slot being provided with a removable plug at the spring-engaging portion thereof for preventing the escape of the intervening springs while moving the plate to the desired channel.

41. In combination with a type-distributing cylinder, provided with a series of peripheral channels, an annular cover-plate for the series of channels mounted concentrically therewith, the cover-plate being provided with a slot coincident with the position of the peripheral channels, which by the rotation of the cover-plate may be brought into register with any one of the channels.

42. In combination with a type-distributing machine, a loading device for the channels thereof, mounted upon a hinged frame whereby it may be swung to and away from its loading position with relation to the channels, and a driving-shaft for the loading device located parallel and in substantial coincidence with the hinge-axis of the frame.

43. In combination with a type-distributing machine, loading mechanism for the type-channels thereof, provided with an actuating-shaft, and pivotally mounted upon the machine, whereby it may be swung into and out of operative relation to the type-channels, the machine being provided with a driving-shaft located in engaging relation to the actuating-shaft of the loading mechanism when the latter is in its operative position.

Corrections in Letters Patent No. 651,551.

It is hereby certified that in Letters Patent No. 651,551, granted June 12, 1900, upon the application of Emil F. Linke, of Hartford, Connecticut, for an improvement in "Type-Distributing Machines," an error appears in the printed specification requiring correction, as follows: In line 126, page 7, the compound word "laterally-moving" should be stricken out, and in line 127, same page, before the word "distributing" the words *laterally moving type* should be inserted; and that the said Letters Patent should be read with these corrections therein that the same may conform to the record of the case in the Patent Office.

Signed, countersigned, and sealed this 11th day of September, A. D., 1900.
